REMOTE PHOTOELECTRIC CONTROL

Carl W. Goodwin, Plainfield, N. J., assignor to
 American Seal-Kap Corporation of Delaware,
 Wilmington, Del., a corporation of Delaware

Application March 12, 1942, Serial No. 434,326

4 Claims. (Cl. 226—88.1)

This invention relates to control systems for electric motors and the like such as are employed in bottle capping machines, and has for its object to provide a new and improved system for controlling such apparatus in accordance with the feed of caps to the machine, without the intervention of objectionable mechanical controls.

Another object of the invention is to provide an improved control system of the above type in which the electrical mechanisms controlling the feed of a machine are enclosed in a protective housing apart from the feeding zone of the machine.

Another object is to provide a feeding mechanism for bottle capping machines with improved means for automatically positioning a succession of stacks of caps in operative relationship with respect to a cap supply chamber.

Another object is to provide a photoelectric relay having novel and improved characteristics.

Another object is to provide a remote control for a photoelectric relay.

Various other objects and advantages will be apparent as the nature of the invention is more fully disclosed.

For purposes of illustration the invention will be described in its application to a machine for applying flexible skirted hood caps to milk bottles or the like, such as is disclosed in the copending application of C. W. Goodwin & H. W. Martin, Serial No. 399,280, filed June 23, 1941.

The capping machine disclosed in the above-mentioned Goodwin & Martin application includes a magazine adapted to contain a plurality of stacks of nested preformed caps which are arranged to be successively brought into operative position to feed the stacks of caps into a supply chamber from which they are successively picked by a picker mechanism and are rolled along a feed chute on the lower edges of their skirts. The cap skirts contain an adhesive which is softened as the caps pass along the feed chute, after which they proceed to a capping station where they are seated on the necks of milk bottles which then advance to a sealing station where the caps are finally sealed in place.

In the machine disclosed in the above-mentioned Goodwin & Martin application, the magazine cooperating with the cap supply chamber comprises a rotatable turret containing a plurality of tubes carrying reserve stacks of caps, which are adapted to successively register with the supply chamber when the turret is rotated by an electric motor. The motor is controlled by a mechanical finger which is normally held in inoperative position by the caps in the supply chamber, but is adapted to be released by the exhaustion of said caps. When so released, the mechanical finger closes an electric contact which energizes the driving motor and thus causes the turret to

rotate until a tube containing a stack of caps is brought into registration with the supply chamber, whereupon such new stack of caps slides downwardly by gravity into the supply chamber and at the same time operates the control finger to shut off the current to the driving motor and thus stop the rotation of the turret.

The foregoing cap-actuated device and associated mechanisms insure a sufficient supply of caps to enable the machine to operate substantially without supervision and without replenishing the cap supply for a considerable period of time.

The present invention provides a new and improved system for controlling apparatus of the above type in accordance with the feed of the machine, without the use of mechanical controls. This is accomplished in accordance with the present invention by controlling the driving motor of the magazine turret through a remote photoelectric relay, and by actuating said relay in accordance with the passage of light through an opening in the cap supply chamber through the intermediary of a rod of a transparent light conducting material having the property of bending and conducting light rays in an irregular path.

Such material may comprise the acrylate and methylacrylate resins, such as resin known as "Lucite," the most common material having the above properties. Various substances having the above properties may be used. In this way, as hereinafter described, the entire mechanism for operating the cap magazine may be enclosed within a protective housing apart from the feeding zone of the machine where it is fully protected when the exposed portions of the machine are to be washed or cleaned.

Although the novel features which are believed to be characteristic of this invention are pointed out more particularly in the claims appended hereto, the invention itself may be better understood by referring to the following description, taken in connection with the accompanying drawing forming a part thereof in which a specific embodiment of the invention has been set forth for purposes of illustration.

In the drawing,

Fig. 1 is a transverse sectional view through the magazine of a capping machine embodying the invention, taken on line 1—1 of Fig. 3;

Fig. 2 is a top plan view of the mechanism shown in Fig. 1; and

Fig. 3 is a transverse longitudinal section taken on the line 3—3 of Fig. 2.

In the following description and in the claims certain specific terms have been used for convenience in referring to various details of the invention. These terms, however, are to be given as broad an interpretation as the state of the art will permit.

Referring to the drawing more in detail, the

invention is shown as applied to a capping mechanism comprising magazine M having a plurality of tubes adapted to contain a plurality of stacks of nested caps for successive application to milk bottles, and from which successive caps are picked by a suitable picker mechanism and supplied to a chute C along which the caps roll and from which they advance through a series of operations until they are finally sealed upon the necks of the bottles, as fully described in the above-mentioned Goodwin & Martin application. Only so much of the Goodwin & Martin machine is shown herein as is necessary to an understanding of the present invention.

The cap magazine is shown in the drawing as comprising a stationary housing 5 attached by a bracket 6 to a suitable pedestal which is adapted to rest upon the floor in a convenient position with respect to the bottle filling machine. A rotatable turret 7 in the form of a hollow casting having a hub 8 is mounted for rotation on a bearing sleeve 9 carried on a stationary pin 10 which is mounted in a boss 12 formed in the housing 5. The turret 7 is provided with a plurality of openings 13 adapted to receive tubes 14 which carry the various stacks of caps 15. The tubes 14 and the corresponding portions of the turret 7 are provided with longitudinal openings 17, which facilitate the manual filling of the tubes with the stacks of caps.

In practice the stacks of caps are usually wrapped in paper to form units corresponding in size and length generally to the tubes 14. The units are inserted as such in said tubes and the stack is unwrapped in situ by unrolling and removing the paper through the longitudinal openings 17. This procedure not only facilitates the loading of the magazine but prevents the caps from being touched by the hand during the loading operation.

The caps 15 may be of the general type disclosed in the copending application of Herbert G. Vore S. N. 391,125, which comprises a center diaphragm or closure portion 18, an annular pouring lip housing 19 and a fluted skirt 20 carrying a band of thermoplastic adhesive on the outer surface thereof as shown in Fig. 1.

The caps 15 are inserted in the tubes 14 with their fluted skirts 20 extending rearwardly and with their diaphragms 18 and pouring lip housings 19 extending forwardly. The magazine M is arranged at an inclination to the horizontal so that the caps feed forwardly by gravity.

The housing 5 is formed with a cap supply chamber 21 with which the successive tubes 14 are adapted to register as the turret 7 is rotated, so that the caps from the corresponding tubes 14 slide downwardly by gravity into the supply chamber 21 when the tubes are properly positioned. The supply chamber 21 has longitudinal openings or slots 22 arranged diametrically opposite each other in the wall of the chamber, as shown in Figs. 1 and 2.

For rotating or indexing the turret 7, a motor 23 is provided driving a worm 24 which meshes with a worm wheel 25 rotatably mounted on the pin 10 and having a key 26 engaging a keyway 27 in the hub 8 of the turret 7. The turret may thus be lifted from the pin 10 and removed for cleaning without disturbing the worm wheel 25 and driving mechanism. The worm gears provide a non-reversible drive to hold the turret against rotation when the motor is stopped. Suitable latch means may be used, however, if desired, to latch the turret in successive feed positions. The sup-

ply chamber 21 is provided at its discharge end with a cap retaining ring 28 which holds the stack of caps in the supply chamber until the individual caps are successively removed by the picker mechanism (not shown) and delivered to the chute C, as described in the above-mentioned Goodwin & Martin application.

In accordance with the present invention, the motor 23 is operated by a motor control relay 29 which, in turn, is actuated by a photoelectric relay 30, both of which relays are entirely enclosed in the main housing 5 of the cap magazine, as shown in Fig. 1. For operating the motor 23 in accordance with the supply of stacks in supply chamber 21, an electric lamp 32 is mounted on the housing 5 adjacent one of the slots 22 in supply chamber 21, and one end 33 of a rod 34 of light conducting material is disposed adjacent the opposite slot 22 in chamber 21 diametrically opposite the lamp 32, so that the rays from lamp 32 may be focused directly on the end 33 of the rod.

The rod 34 projects through an opening in housing 5 and is tightly sealed therein by a gasket 35 of rubber or other suitable material, the rod being bent as required to bring its inner end 36 adjacent the photoelectric activating element of relay 30 as shown in Fig. 1. The rod may be made in two or more sections if desired. When the supply chamber 21 is filled with a stack of caps, the caps will obstruct the passage of light from lamp 32 to the end 33 of the rod 34, and under such conditions the photoelectric relay 30 will be deenergized. However, when the entire stack of caps has been fed past the field of lamp 32, the light from said lamp will pass through the diametrically opposite openings 22 in chamber 21 and impinge upon the end 33 of rod 34. Due to the unique property of said light conducting material the light focused on the end 33 of rod 34 will be conducted through the entire length of the rod, including the bent portions thereof, and be focused upon the photo-active element of the photoelectric relay 30. Thereupon, the photoelectric relay 30 actuates the motor control relay 29, setting the motor 23 in operation.

The motor 23 accordingly drives the worm wheel 25 and causes the turret 7 to rotate slowly. This rotation of the turret continues until a tube 14 containing a supply of caps 15 is brought into registration with the supply chamber 21. When this occurs, the stack of caps in the tube 14 slides downwardly into the supply chamber, obstructing the passage of light from lamp 32 through the slots 22 in the wall of chamber 21. Thus cuts off the light to photoelectric relay 30 and thereby stops the motor 23. The turret 7 remains in this position until the supply of caps in the tube 14 cooperating with the supply chamber 21 is exhausted, after which the above described operation is repeated to bring a new tube 14 into supply position. The empty tubes 14 may be manually filled from time to time as required. In this way a large number of caps is maintained at all times in the magazine M.

An important feature of the invention, as described above, is that the entire mechanisms for operating the magazine M, including motor 23 and associated elements, motor control relay 29, and photoelectric relay 30, are enclosed within the main housing 5, even the rod 34 being sealed in said housing by the gasket 35, so that all of said mechanisms are fully protected when the exposed portions of the machine are to be washed

or cleaned. Furthermore, due to the novel combination of elements above described, the motor 23 and its associated operating mechanisms may be mounted compactly and conveniently within the housing 5, the rod 34 being bent as required for this purpose, and enabling the mechanisms within the housing to be operated in accordance with the supply of caps to the chamber 21 which is disposed outside said housing.

It is to be understood that a specific use of the remote controlled photoelectric relay has been set forth for illustration only. The relay is capable of various uses in cases where the source of light is to be located at a point removed from the photoelectric cell. The light path, including said rod 34, may have a gap at any convenient point to permit the insertion of a member to interrupt the light rays for operating the photoelectric relay. Hence both the photoelectric cell and the light source may be located at points remote from the actuating member. Furthermore, the rod 34 prevents unauthorized operation of the relay by accidentally blocking the light rays at points other than the intended position of the operating member.

Although a specific embodiment of the invention has been shown for purposes of illustration, it is to be understood that various changes and modifications may be made therein as will be readily apparent to a person skilled in the art. Furthermore, the features set forth above may be applied to other types of capping machines and for other uses and are not restricted to the specific combination disclosed. The invention is only to be limited in accordance with the scope of the following claims.

What is claimed is:

1. In a machine for applying to containers and sealing thereon partially preformed hood caps having foldable pleated skirts, a supply chamber containing a stack of said caps to be fed therewith by gravity for successive removal and application to bottle necks, a supply magazine containing a plurality of reserve stacks of caps, driving means actuating said magazine to successively advance said reserve stacks into position for feeding into said supply chamber, means including a photoelectric relay for actuating said driving means, a light source mounted to be normally obstructed by the caps in said supply chamber and to direct light rays through said chamber upon the exhaustion of such caps therein, and means cooperating with said light source for focusing the unobstructed light rays upon said photoelectric relay to actuate said driving means.

2. In a machine for applying to containers and sealing thereon partially preformed hood caps having foldable pleated skirts, an inclined supply chamber containing a stack of said caps to be fed therewith by gravity for successive removal and application to bottle necks, a supply magazine containing a plurality of reserve stacks of caps, said magazine comprising a rotatable turret, driving means to rotate said turret, a photoelectric device remote from said supply chamber for actuating said driving means, a light source mounted to be normally obstructed by the caps in said supply chamber and to direct light rays through said chamber upon the exhaustion of such caps therein, and a rod of light conducting material having one end arranged to receive unobstructed light rays passing through said supply chamber and the other end arranged to focus such light rays upon said photoelectric device to actuate said driving means and thereby automatically advance said turret when one supply of caps in said supply chamber has become exhausted.

5 such caps therein, and a rod of light conducting material having one end arranged to receive unobstructed light rays passing through said supply chamber and the other end arranged to focus such light rays upon said photoelectric device to actuate said driving means and thereby automatically advance said turret when one supply of caps in said supply chamber has become exhausted.

10 3. In a machine for applying to containers and sealing thereon partially preformed hood caps having foldable pleated skirts, an inclined supply chamber containing a stack of said caps to be fed therewith by gravity for successive removal and application to bottle necks, a supply magazine containing a plurality of reserve stacks of caps, said magazine comprising a rotatable turret, a plurality of stack receiving tubes spaced peripherally around said turret and carried thereby, said tubes being adapted to successively register with said supply chamber as said turret is rotated, driving means remote from said supply chamber for rotating said turret, a closed housing for said driving means, a photoelectric device in said housing for actuating said driving means, a light source mounted to be normally obstructed by the caps in said supply chamber and to direct light rays through said chamber upon the exhaustion of such caps therein, and a rod of light conducting material extending through said housing and having one end arranged to receive unobstructed light rays passing through said supply chamber and the other end arranged to focus such light rays upon said photoelectric device to actuate said driving means and thereby automatically advance said turret when one supply of caps in said supply chamber has become exhausted.

15 4. In a machine for applying to containers and sealing thereon partially preformed hood caps having foldable pleated skirts, an inclined supply chamber containing a stack of said caps to be fed therewith by gravity for successive removal and application to bottle necks, a supply magazine containing a plurality of reserve stacks of caps, said magazine comprising a rotatable turret, a plurality of stack receiving tubes spaced peripherally around said turret and carried thereby, said tubes being adapted to successively register with said supply chamber as said turret is rotated, driving means remote from said supply chamber for rotating said turret, a sealed housing containing said driving means, a photoelectric device in said housing for actuating said driving means, a light source mounted to be normally obstructed by the caps in said supply chamber and to direct light rays through said chamber upon the exhaustion of such caps therein, and a rod of light conducting material extending through said housing and having one end arranged to receive unobstructed light rays passing through said supply chamber and the other end arranged to focus such light rays upon said photoelectric device to actuate said driving means and thereby automatically advance said turret when one supply of caps in said supply chamber has become exhausted, said Lucite rod being bent within said housing and sealed therein to render said housing water-tight.
